CLAIM

The ornamental design for a partitioned dispensing container, substantially as shown and described.

DESCRIPTION

FIG. 1 is a perspective view of a partitioned dispensing container showing our new design;

FIG. 2 is a rear elevational view thereof;

FIG. 3 is a side elevational view thereof taken from the right in FIG. 2;

FIG. 4 is a top plan view thereof;

FIG. 5 is a bottom plan view thereof; and

FIG. 6 is an exploded perspective view thereof.

FIG. 1

FIG. 2

FIG. 3

FIG. 4

FIG. 6

FIG. 5
